US0D1067948S

(12) **United States Design Patent** (10) Patent No.: **US D1,067,948 S**
(45) Date of Patent: ** Mar. 25, 2025

(54) **IMMERSION PUMP**

- (71) Applicant: **Hysypro AG**, Wolfenschiessen (CH)
(72) Inventor: **Philipp Stempfle**, Neuburg (DE)
(73) Assignee: **HYSYPRO AG**, Wolfenschiessen (CH)
(**) Term: **15 Years**
(21) Appl. No.: **35/518,489**
(22) Filed: **Sep. 8, 2023**

(80) **Hague Agreement Data**

- Int. Filing Date: **Sep. 8, 2023**
Int. Reg. No.: **DM/231643**
Int. Reg. Date: **Sep. 8, 2023**
Int. Reg. Pub. Date: **Sep. 29, 2023**

(30) **Foreign Application Priority Data**

- May 9, 2023 (CH) 147451
(51) LOC (15) Cl. 15-02
